TRANSVERSELY GAPPED CYLINDRICAL
ANTENNA

Andrew Alford, Cambridge, Mass.

Application June 19, 1946, Serial No. 677,653

15 Claims. (Cl. 250—33)

1

This invention relates to new and useful improvements in antennas and particularly in mobile transmitting and receiving antennas for use on automobiles, buses, trains, aircraft and the like.

In the art of radio transmission where at least one station is mobile it is the general practice to employ vertically polarized radio frequency waves, since they have good field strength near to the ground.

A simple and widely used antenna for such waves is a vertical flexible whip antenna. This antenna has several serious shortcomings. In order to function efficiently it must be near to a quarter wave length long, a length at which it is resonant and has a narrow pass band. The pass band can be broadened by increasing the thickness of the radiating element, but it then may cease to be a whip antenna and may present too rigid and hazardous a projection from a moving vehicle. The band width of an ordinary quarter wave whip antenna is of the order of ten percent (.10) and, even if compensating circuits are used, this can only be increased to approximately twenty-five percent (.25).

If the length of a whip antenna is reduced below a quarter wave length, then its radiation resistance will become materially lowered and its input impedance will include capacitive reactance. The expedient of tuning out this reactance with a coil will further decrease the efficiency of the antenna and its already small band width.

Tilting a vertical whip antenna away from its perpendicular position, so as to lower the height of its tip, will diminish both its band width and its radiation resistance.

At the relatively high frequency of 156 mc., a quarter wave length whip would be all of sixteen inches long. A sixteen-inch protrusion from the top of a vehicle as high as a bus, or a truck, or a railroad car can be very troublesome. Such vehicles frequently are built nearly as high as the minimum head-room tolerance legally permitted for bridges, tunnels, viaducts and terminals. Moreover, in certain areas such obstructions would most likely encounter low hanging branches of trees.

Foldable mounting of a whip antenna to avoid overhead obstacles will make continued operation of associated radio equipment impossible. Furthermore, such a mounting, as well as one permitting the whip antenna to tilt when striking an object, will necessitate complicated and expensive flexible feed line means and will add to servicing requirements.

A whip antenna attached to some part of a

2

vehicle below the level of the roof, such as on a running board or bumper, will always be masked in some direction by the body of the vehicle.

Another possible objection to whip antennas is that they are conspicuous and easily identified and may, therefore, constitute an obvious clue to the presence of radio equipment in a vehicle and to the type of vehicle it is, for example, that it is a special police car.

10 The protrusion of whip antennas is objectionable on aircraft for the additional reasons that at ordinary high speeds they produce substantial drag, and at very high speeds their drag attains not only inordinately large magnitudes, but the vibration will either break off the antenna or damage the aircraft.

Among the objects of this invention are to provide a vertically polarized transmitting or receiving antenna having a band width of 1.2, a substantially circular radiation pattern in horizontal planes, and one which is very compact and therefore will, when installed on a vehicle, present a minimum protrusion.

With this object in view I provide a hollow conducting body having a transmission line formed therein intermediate its ends. Preferably, the transmission line is constituted by a transverse gap in the side wall of a cylinder, which returns on itself and with which the feeder is connected. The hollow conducting body is connected with, and preferably mounted on, a flat conducting surface, e. g. the surface of a vehicle.

According to one of the features of the present invention, if a cross sectional area of the space within said cylinder, taken in a plane through its axis, is of the order of one-hundredth of a wave length squared, then the structure will satisfy the above-mentioned objects.

Reference is made to my copending application U. S. Serial No. 669,758, filed May 15, 1946, now Patent No. 2,508,084, granted May 16, 1950, although part of its disclosure will be repeated for the convenience of the reader and to facilitate the understanding of the present invention.

45 Other objects, features and advantages of this invention will become apparent to those familiar with the art from the following description, and the appended claims and drawings, in which:

Fig. 1 is an isometric view, partly cut away, of the radiating element of one embodiment of the antenna;

Fig. 2 shows the antenna of Fig. 1 in combination with a conductive ground plane;

Fig. 3 is a transverse cross sectional view of the antenna shown in Fig. 2, the cross section being taken along line 3—3 of Fig. 2; and

Fig. 4 shows a modification of the form shown in Fig. 1.

Referring now more particularly to Fig. 1, the radiating element shown therein consists of two principal circular body elements 1, 2 which may be metallic castings or spinnings shaped like pie plates. These elements include as respective integral parts thereof bottom discs 3, 4 and up-standing rims attached thereto, which, in the figure, bear the above-mentioned numerals 1 and 2. Body elements 1, 2 are joined by a tube 5 which is mechanically attached to inside surfaces of bottoms 3 and 4 at substantially their centers. In practice tube 5 may be formed as an integral part either of element 1 or of element 2 and then the main assembly will consist of two parts. Tube 5 may be of metal and as a result will be conductive. However, the inside portion of tube 5 joins areas of the outer sides of discs 3 and 4 where R. F. voltages are of zero (or extremely low) potential and, therefore, the inside may be non-conductive without preventing this device from functioning. On the other hand, it will do no harm to its functioning if the inside of the tube is a good conductor. The outer surface of tube 5 whose surface is part of the inner surface of the hollow cylinder (composed of elements 1 and 2), should be conductive as there must be a low impedance axial connection between the inner surfaces of elements 1 and 2. Where a metallic supporting mast is used the portion of it which passes through the hollow cylinder may take the place of tube 5. Its outer skin will perform this conductive function and there will be no need for tube 5, except that 5 ordinarily serves as a convenient gauge for properly spacing 1 and 2.

Tube 5 is of such length and is so arranged that body elements 1 and 2 do not touch each other; it holds them with their bottom discs 3 and 4 parallel and their rims evenly separated by a gap 6. Gap 6 may be an air gap and is so shown in the drawing. However, it may be physically sealed by a dielectric substance so long as the area of the gap still remains non-conductive, in the ordinary sense, and constitutes a "hiatus" in the conductive surfaces of the cylinder 1, 2 wherever it intercepts them. Gap 6 is short-circuited by metal band 7.

Bottoms 3 and 4 have centrally located holes which register with the ends of the annular opening through tube 5. The entire structure 1-7 may be described as a hollow body or cylinder whose ends are closed by discs 3, 4 and whose side walls have a gap 6 which runs round the cylinder in a plane parallel to and midway between discs 3 and 4, and returns on itself, the cylinder halves being held together by an internally located axial tube fastened to the inside surfaces of discs 3 and 4.

The hollow cylinder may be made of solid sheet metal (or an equivalent, such as solid sheet plastic including a conductive layer) and, accordingly, the inner and outer areas, will comprise wall surfaces physically unbroken except for gap 6. However, this physical continuity is not necessary and the device will operate satisfactorily if made of wire screen or of perforated sheet metal if the openings are not too large with respect to one wave length corresponding to the highest operating frequency, e. g. not larger than $\frac{1}{100}$ of a wave length.

The antenna is energized over a coaxial transmission line having an outer conductor 8 and inner conductor 9. Inner conductor 9 is connected

to the edge of the rim of body element 1, and the outer conductor 8 is similarly connected to element 2. These connections are made at points opposite each other across gap 6, and this part of the gap is at a place on the side of the hollow cylinder which is diametrically opposite the position of short-circuiting band 7.

In Fig. 1 the radiating element is shown mounted on a mast 10. For reasons already explained, the mast may be conductive and, therefore, may be of metal such as steel. It passes through tube 5 and through the centrally located holes in bottoms 3 and 4. The antenna may be prevented from sliding up or down the mast by suitable collars or clamps similar to the one which is shown in the drawing, in a displaced position at 10a. The coaxial transmission lines 8, 9 may be clamped to mast 10 and to element 2 by any suitable means.

When the antenna is energized the adjacent edges of the cylinder halves, i. e. the edges of gap 6, constitute a balanced transmission line. The hollow body portion of this antenna (which may be further described as surrounding and enclosing a toroidal space about the outer perimeter of which gap 6 is located) has distributed inductive reactance which is shunted across this transmission line. The magnitude of this distributed reactance depends primarily on the area of a transverse cross section, taken in a plane through the longitudinal axis of mast 10, of the toroidal space on one side of tube 5. This is the space between the inner surfaces of elements 1, 2 and the outer surface of tube 5. If the inside radius of the hollow cylinder is designated as D, the outer radius of the tube 5 as d, and the distance between the inner surfaces of bottoms 3 and 4 as H, then this cross sectional area may be calculated by using the formula $A = (D-d) \times H$. Certain cylinders, which have proper magnitudes of distributed reactance and perform in a preferred manner as radiators in accordance with this invention, have such dimensions that, when converted into wave lengths, the area derived by solving the equation is $A = .0105\lambda^2$.

Short-circuiting band 7 causes nearly complete reflection of incident waves traveling along gap 6 around both sides of the hollow cylinder toward it. The interference between incident waves and reflected waves results in a standing wave distribution of voltage across gap 6.

One minimum of voltage across the gap occurs at shorting band 7; two maxima of voltage occur at points on opposite sides of the hollow cylinder 55 each of which is about midway between band 7 and the feed point. Under certain conditions, two additional voltage minima, which ordinarily are undesirable, may occur on gap 6. They will be between band 7 and the feed point and are likely to be near to, and on each side of, the feed point. A condition which may cause this is that the gap is too long in proportion to the cross sectional area A and that, therefore, the velocity of propagation along the gap is not great enough for the gap length.

When the only voltage minima are at the shorting band and the feed point, the voltage differences across gap 6, though they vary in magnitude, are in the same phase, and currents moving between the edges of gap 6 and the disc bottoms move in the same direction.

It has been empirically ascertained in actual tests, and it can be further demonstrated in other ways, that this in-phase condition of the R. F. voltages across gap 6 and the geometric shape of

the hollow cylinder will cause this element to act as a horizontally omnidirectional radiator of vertically polarized energy, assuming, of course, that the axis of tube 5 is perpendicular to the ground.

When undesired voltage minima occur between the feed point and band 7 (along the gap 6 on each side of the hollow cylinder), the phases of the R. F. voltages near those minima shift rapidly. This alters the current distribution pattern and results in asymmetry of the horizontal radiation pattern. The hollow cylinder should preferably be so proportioned that the distances from band 7 to the first voltage minima (or to imaginary positions of the first minima constructively existing beyond the feed point) in each direction around the hollow cylinder, are equal to (or greater than) one-half of the circumference of the cylinder.

The desired standing wave condition can be obtained even when gap 6 is greater than $\lambda/2$ in length by sufficiently increasing the velocity of propagation along the gap, even substantially beyond the speed of light under certain conditions. This is controlled in part and within limits by the cross sectional area described above and by the capacity per unit length between the edges of the gap.

A cross sectional area $A = .0105\lambda^2$, together with a gap which is of the order of $.0048\lambda$ wide and is formed by thin metal edges, results in a velocity of propagation along the gap about twenty percent greater than the velocity in free space. This permits the use of a cylinder whose circumference is proportionally increased so that each half circumference is in the neighborhood of twenty percent more than a half wave length. The physical enlargement of the hollow cylinder with respect to the operating wave length, which is effected at the same time that undesired voltage minima are averted, will make its input impedance low enough to match a 50-ohm coaxial line. Thus, in addition to being compact and vertically polarized (when properly positioned with respect to the earth), the device requires no input transformer, making it an ideal coupling between a 50-ohm cable and the radiation resistance of space.

One example of satisfactory proportioning of the several parts of the antenna is the following: $D = .32\lambda$, $d = .32\lambda$, $H = .072\lambda$ and $g = .0048\lambda$. These dimensions are expressed in terms of a wave length corresponding to the middle frequency of the operating band of frequencies. Where that middle frequency is 378 mc. and these dimensions are converted into inches, they are $D = 10''$, $d = 1''$, $H = 2\frac{7}{16}''$ and $g = \frac{3}{16}''$. When mounted so that 1 or 2 is in contact with ground (Figs. 2 and 3), H should be reduced to one-half of this amount, i. e. $1\frac{3}{32}''$. Obviously, if the operating frequency is changed, all of the physical proportions of the antenna should be proportionally changed.

It should be borne in mind that the controlling geometric characteristic for a gap which has a fixed amount of distributed capacitance per unit length, is the cross sectional area described above. For example, d may be made larger with respect to D , reducing the value of $D - d$, but by increasing H by an easily determined amount, A will remain substantially the same and the standing wave condition will be substantially unchanged.

Moreover, the hollow cylinder may be shaped so that its toroidal cross section on each side of the central tube is of other shapes than rectangular. This cross section may be circular, elliptical or irregularly shaped. In the same

manner, it is not essential that cross sections of the hollow cylinder, taken in planes perpendicular to the axis of tube 5, should be circular. The important factors are that A be generally of the order of $.0105\lambda^2$ and that the exact value of A can vary depending upon the capacitive characteristics of the gap. In this application, and in particular in the claims, the word "cylinder" is used in a broad sense to indicate all hollow structures which electrically conform with the requirements of the invention, though they are not necessarily geometric cylinders having circular transverse cross sections.

The antenna produces substantially circular radiation patterns in horizontal planes, i. e. planes perpendicular to the axis of tube 5, and figures-of-8 vertical patterns in planes passing through that axis. The band width of the antenna is of the order of 1.2.

Obviously the antenna described above may be employed at frequencies and for purposes other than those given above by way of exemplification.

Referring now to Fig. 2, a radiating element similar to that of Fig. 1 is attached to a conductive ground plane 11, which may be a metal sheet, with disc 4 of the radiating element juxtaposed to it. In practical use, ground plane 11 may be attached to the roof of a vehicle or form an integral portion thereof, and does not have to be perfectly flat. As well known, a ground plane of finite size, above a certain limit, will behave like an infinite reflective plane and affect the radiation patterns of any radiator associated with it; a physically infinite plane is unnecessary. Similarly, a substantially flat ground plane will, at ordinary wave lengths, behave like a perfectly flat ground plane. Therefore, the curved metal roof of a vehicle may serve as ground plane 11.

It is obvious that ground plane 11 will affect the vertical distribution pattern of the radiator. However, this is not a disadvantage. If the antenna is close to the earth, e. g. on the roof of a bus, the areas masked by the ground plane will be unimportant. Even if the antenna is not close to the earth, i. e. if it is in an airplane, the vertical masking is not a disadvantage. For in an aircraft installation the radiating element could be installed on the underside of the surface acting as a ground plane. The important patterns, those in horizontal planes, are not appreciably affected.

The presence of ground plane 11 affects both the velocity of propagation and the standing wave along the gap. Therefore, if a ground plane is used, the proportioning of the antenna body should be appropriate to compensate for its presence. Its cross sectional area A should be about one-half as great as that of a corresponding antenna of the type shown in Fig. 1.

The non-conductive space inside the hollow cylinder need not necessarily be filled with air. Instead, other dielectrics may be used including dielectrics which are gases, liquids and solids. However, substances whose dielectric constants differ from that of air will increase the distributed capacity and reduce the velocity of propagation. The proportions of the hollow cylinder should, therefore, be somewhat altered. Other changes and adaptations will readily suggest themselves to those skilled in the art.

The shorting element which has been described in the present application as located on the side of the slot diametrically opposite to the feed point need not in practice be of exactly zero impedance.

The terms "short circuit" and "short-circuiting element" as used herein, both in the description and in the claims, are intended to include low impedance terminations, such as a wire or coil having low inductance, which are capable of producing substantial percentages of reflection.

Moreover, it is also within the scope of this invention that another feed line as shown in Figure 4 be connected at the point designated for the location and in lieu of the shorting element as indicated by the feeders 8' and 9'. The desired standing wave condition on the gap or slot can be produced with this two feed point arrangement just as well as by one in which there is a single feed point and a reflection point or low impedance point diametrically opposite to it. It has been found that usually a double feed affects the operating characteristics of the antenna by broadening the operating frequency band.

What I claim is:

1. In an antenna, a hollow conducting body having continuous side walls, and end walls positioned opposed to one another at opposite ends of the hollow body, said side walls having a linear discontinuity extending around the side walls and spaced from the end walls, a conducting element within the hollow body, extending between the end walls and electrically connected thereto, means having a flat conducting surface on which the hollow conducting body at one of its ends is mounted, said linear discontinuity forming an air gap with the conductive material adjacent both sides of the gap forming a transmission line about the hollow body, and a feeder connected to the body with one terminal thereof connected to one side of the transmission line and the other terminal to the other side.

2. The antenna according to claim 1, and in which the transmission line forms a closed loop in the side walls of the hollow conducting body.

3. The antenna according to claim 1, and in which the transmission line forms a circular loop in the side walls of the hollow conducting body.

4. The antenna according to claim 1, and in which the transmission line forms a closed loop in the side walls of the hollow conducting body, and short circuit means connected across the line opposite the connection of the feeder.

5. The antenna according to claim 1, and in which the transmission line forms a circular loop with both sides of the line in a common vertical cylindrical surface, and short circuit means connected across the line near a point half the way around the loop from where the terminals of said feeder are connected.

6. The antenna according to claim 1, in which the transmission line forms a closed loop having a low-impedance radio frequency reflecting means connected across the transmission line at a point half the way around the loop from where the terminals of said feeder are connected.

7. The antenna according to claim 1 having a second feeder connected across the transmission line at a point half the way around the loop from where the terminals of said feeder are connected.

8. An antenna comprising a conducting cylinder closed at both ends and having a gap formed in the material around the body of the cylinder intermediate its ends providing two portions, a 70 conducting surface attached to one end of the cylinder, a conductor extending axially within the cylinder and holding the two portions spaced to form said gap between opposing edges of the two portions, a feeding line having one conductor 75

connected with one and the other conductor with the other portion of the cylinder near said gap, and short circuit means across the gap at a point diametrically opposite the points of connection of the feeding line.

9. The antenna according to claim 8, and in which the gap divides the cylinder into halves.

10. The antenna according to claim 8, and in which the cross-sectional area of the space within the cylinder taken in a plane containing its axis and on one side of the conductor being substantially one-hundredth multiplied by the wave length squared wherein said wave length is the wave length corresponding substantially to the center frequency of the transmission band.

11. The antenna according to claim 8, and in which the diameter of the cylinder is substantially $.32\lambda$ where λ is the wave length corresponding to the center frequency of the operating transmission band.

12. The antenna according to claim 8, and in which the height of the cylinder is substantially $.036\lambda$ where λ is the wave length corresponding to the center frequency of the operating transmission band.

13. The antenna according to claim 8, and in which the width of the gap is a small fraction of a wave length corresponding to the center frequency of the operating transmission band.

14. An antenna comprising a metal cylinder substantially $.05\lambda$ high where λ is the wave length corresponding to the center frequency of the operating transmission band closed at both ends and having a circular gap around it parallel with and midway between the ends, said cylinder having a circular cross section substantially $.44\lambda$ diameter, a metal plate on which one end of the cylinder is mounted, a metal tube having its ends fastened to the ends of the cylinder and holding the edges of the cylinder halves to form said gap substantially $.0048\lambda$ wide, the diameter of said tube being substantially $.273\lambda$, a concentric feed line having an inner conductor connected with one and an outer conductor with the other half of the cylinder near said gap, and short circuit means across the gap at a point diametrically opposite the points of connection of the feed line to the cylinder.

15. In an antenna, a hollow conducting cylinder, having between the ends thereof a gap in its side wall providing thereby a closed loop, a means providing a conductive closure for one end of the cylinder wholly within the side wall thereof, means providing a conductive closure for the other end of the cylinder extending beyond the side wall in a plane perpendicular thereto, a conductive connection between the closures connected therewith near the axis of the cylinder, and means for feeding the cylinder near the gap.
